UNITED STATES PATENT OFFICE.

ELLA LE GORE NICHOLS, OF KANSAS CITY, MISSOURI.

SANITARY TOILET-SEAT COVER.

1,225,673.

Specification of Letters Patent.

Patented May 8, 1917.

Application filed November 3, 1913. Serial No. 798,852.

To all whom it may concern:

Be it known that I, ELLA LE GORE NICHOLS, a citizen of the United States, residing at Kansas City, in the county of Jackson and State of Missouri, have invented certain new and useful Improvements in Sanitary Toilet-Seat Covers, of which the following is a specification.

My invention relates to sanitary toilet seat covers, and my principal object is to provide a simple, inexpensive device of this character which can be readily placed in position on a toilet or closet seat to prevent the spread of infectious diseases.

Another object is to provide a device of this character which is adjustable to accommodate toilet seats of different sizes.

A further object is to provide a device of this character which can be folded into such shape as to render it easily dispensable from coin-controlled vending machines located in depots, hotels, and other public places.

In order that the invention may be fully understood, reference will now be made to the accompanying drawings, in which:

Figure 1 is a broken detail perspective view of the upper portion of the toilet with the seat thereof provided with one of my sanitary covers.

Fig. 2 is a longitudinal section of the toilet seat and cover on line II—II of Fig. 1.

Fig. 3 is a vertical cross section on line III—III of Fig. 2.

Fig. 4 is a detail plan view of the sanitary toilet seat cover.

Fig. 5 is a detail perspective of the sanitary toilet seat cover in the folded position it will occupy when delivered from a vending machine.

Fig. 6, is a fragmentary rear elevation of the seat cover showing the folded flap.

In carrying out the invention, I employ a sheet of paper or other suitable material 1, having an opening 2 and of approximately the contour of the ordinary toilet seat 3, it being understood that said cover 1 may be made in various shapes to fit different shaped toilet seats.

Cover 1 has inner and outer downturned 50 margins 4 and 5 to fit over the inner and outer margins 6 and 7, respectively, of the toilet seat to keep the body of the user from contacting said seat and also preventing said seat from becoming soiled. 55

The front side of the inturned margin 4 has a depending shield 8, which extends down into the hopper 9 of the toilet, to prevent contact of the user therewith.

The central rear portion of the cover 1 60 is folded as disclosed at 10, so that said cover may be adjusted as indicated by the dotted lines, (Fig. 4) to accommodate a larger toilet seat, and to constitute a flap which may be used in lieu of toilet paper if desired. 65

Cover 1 is held in position upon the toilet seat by a pair of oppositely disposed resilient clasps 11, secured to the underside of the toilet seat and extending upwardly and partly over the same to overlap the 70 adjacent margins of the cover 1, which are placed beneath the seat clasps.

From the foregoing description, it is apparent that I have produced a simple, inexpensive cover which may be readily placed 75 in position over a toilet seat and prevent the spread of disease by preventing the body from contacting said toilet seat.

Having thus described my invention, what I claim and desire to secure by Letters Patent is:

A sanitary cover for toilet seats comprising a ring-like body having a flap, said flap and body being folded to provide an overlapping portion extending in a line radially 85 of the latter to vary the size of the body and said tongue being further folded transversely onto the body to constitute a lock for the overlapped portion of the latter.

In testimony whereof I affix my signature, in the presence of two witnesses.

ELLA LE GORE NICHOLS.
